CLAIM

The ornamental design for an antenna for a storage disc, as shown.

DESCRIPTION

FIG. 1 is a perspective view of an antenna for a storage disc showing our new design;

FIG. 2 is a top plan view thereof;

FIG. 3 is a top plan view of a second embodiment thereof;

FIG. 4 is a top plan view of a third embodiment thereof; and,

FIG. 5 is a top plan view of a fourth embodiment thereof.

The broken line drawing in all views of an optical storage disc is for illustrative purposes only and forms no part of the claimed design.
